UNITED STATES PATENT OFFICE.

ALBERT E. STEWART, OF FRANKLIN, NEW HAMPSHIRE, ASSIGNOR TO ACME KNITTING MACHINE AND NEEDLE COMPANY, A CORPORATION OF NEW HAMPSHIRE.

KNITTING-MACHINE.

1,315,725.

Specification of Letters Patent. Patented Sept. 9, 1919.

Application filed July 19, 1917. Serial No. 181,496.

To all whom it may concern:

- Be it known that I, ALBERT E. STEWART, a citizen of the United States, and a resident of Franklin, county of Merrimack, and 5 State of New Hampshire, have invented Improvements in Knitting-Machines, of which the following is a specification, reference being had to the accompanying drawings, forming part thereof.
- 10 This invention has reference to improvements in knitting machines and more particularly to improvements in hosiery knitting machines.
- Heretofore it has been customary to knit 15 the toe pocket of a stocking on the same side of the foot as the heel pocket, thus causing the closing seam at the toe to be located across the upper part of the foot. I have found, however, that a more comfortable 20 stocking is produced by knitting the toe pocket on the top side of the foot diagonally opposite to the heel pocket, thereby causing the closing seam at the toe to be located across the underside of the foot; and it is 25 the main object of the present invention to provide efficient means, in a knitting machine, for accomplishing the knitting of the toe pocket in this desired position relative to the heel pocket.
- 30 Other objects of the invention will appear from the following description.

The invention consists in the herein described means for causing the needle cylinder to lose one-half revolution preparatory 35 to the knitting of the toe pocket of the stocking.

The invention further consists in the herein described means for selectively raising the short butt needles into inoperative 40 position while the long butt needles remain in operative position.

The invention further consists in the herein described means for respectively knitting the heel and toe pockets of a stocking 45 with the short and long butt needles.

The invention still further consists in such other novel features of construction, operation and combination of parts as shall hereinafter be described and pointed out in the 50 claims.

Referring to the drawings:

Figure 1, represents a plan view in eleva-

tion of a knitting machine embodying my invention.

Fig. 2, represents a side view in elevation 55 of a portion of the same.

Fig. 3, represents a sectional view, partly 58 in elevation, taken on the line 3—3 of Fig. 1.

Fig. 3^a, represents a reduced sectional view 60 taken on the line a—a of Fig. 3.

Fig. 4, represents an enlarged plan view 65 in elevation of a portion of my improved needle elevating mechanism, showing its relative position to the needle cylinder and needles which are shown diagrammatically in plan view.

Fig. 5, represents a sectional view, mostly 68 in elevation, taken on the line 5—5 of Fig. 4.

Fig. 6, represents a sectional view taken 70 on the line 6—6 of Fig. 4.

Fig. 7, represents a side view in elevation 75 of the foot of a stocking knit by my machine.

Like characters of reference designate corresponding parts throughout.

The machine shown in the drawings, 75 which is of the general construction, as the one shown in my copending application, filed March 19, 1917, Serial No. 155,732, is provided with the usual main cam drum shaft 10 operated in the usual manner 80 through mechanism connecting it with the driving pulleys 11. The latter also impart the usual rotary and reciprocating rotary movements to the shaft 12, through suitable mechanism forming no part of the present 85 invention. In mesh with the usual gear 13 carried by said shaft 12, is the gear 15 which I journal on the hub of the miter gear 16 loose on stud 17 projecting from the frame of the machine. Said miter gear 16 meshes 90 with miter gear 19 keyed in the usual manner to needle cylinder 20.

Concentric with said stud 17 and loosely mounted on bearing 21 projecting from the frame, I provide the clutch hub 23 having clutch pins 25 extending into the apertures 26 in said gear 15. Miter gear 16 is provided with a series of apertures 27 adapted to receive the ends of clutch pins 25 when said clutch hub is shifted. The latter is 95 provided with the annular groove 29 engaged by stud 30 on the upper end of the cam lever 31. Said cam lever 31 is pivoted at 32 on the cross bar 33 of the frame and its

lower end is sustained in engagement with the cam 35 mounted on said drum shaft 10, by the spring 36.

The usual switch cam 37 is secured to the inner end of sliding pin 39, and is located above and concentric with the raceway 40 of the stationary cam cylinder 41. Said sliding pin 39 is mounted to slide in the bearing 42 projecting upwardly from the bed plate 43 of the machine frame. The outer end of said sliding pin is reduced to form the shoulder 45 corresponding to shoulder 46 in said bearing 42. The retracting spring 47 is attached at one end to the forward end of sliding pin 39 and its other end is attached to said bearing 42. The outer end of said sliding pin is engaged by one end of the cam lever 49 pivoted on the upright stud 50 projecting from said bed plate 43, and the other end of said lever is in the path of the cams 51 and 52 on the cam disk 53. The latter is mounted on one end of the usual yarn change drum shaft 54. The cam 55 is also carried by said cam disk and is adapted to engage one end of the cam lever 57 pivoted on said stud 50. The forward end of cam lever 57 is provided with the horizontal bearing 58 for the plunger 59. Between the shoulder 60 on said plunger and shoulder 61 on bearing 58 is the expansion spring 62, and on the outer end of said plunger is the stop pin 63. The inner end of said plunger engages the outer end of auxiliary cam 64, which consists of a transversely inclined bar mounted to slide on the block 65 projecting from bed plate 43, and having its inner end approximately concentric with the needle cylinder. Said auxiliary cam is guided by headed screws 67 threaded into said block 65 and extending through the elongated aperture 68 in said auxiliary cam. The latter is pressed outwardly by the retracting spring 69 having one end attached thereto and the other end attached to the bed plate.

The bar 40^a of said raceway 40 is cut away at 40^b to form the inclined surface 40^c parallel to the inclined surface 64^a of auxiliary cam 64, and the inclined surface 40^d parallel to the under surface of switch cam 37.

Arranged about the needle cylinder in the usual manner are an even number of short butt needles *s* and long butt needles *l*. In the operation of the machine, all of the stocking, with the exception of the toe pocket, is knitted in the manner described in my said copending application; the switch cam in the present case, however, being positioned by cam 52 through cam lever 49 to raise the long butt needles into inoperative position preparatory to the knitting of the heel pocket by the short butt needles.

The necessary continuous rotary and reciprocating rotary movements are imparted

to the needle cylinder from shaft 12, through gear 13, gear 26, clutch pins 25, miter gear 16, and miter gear 19. Before the completion of the continuous rotary knitting of the foot, preparatory to the reciprocating rotary knitting of the toe pocket, miter gear 16 is disconnected from gear 15 by the withdrawal of pins 25 from aperture 27. Pins 25 are withdrawn by the action of cam 35 through cam lever 31 and clutch hub 23. Immediately after the withdrawal of clutch pins 25, cam 35 permits spring 36, through the connecting mechanism, to return clutch pins 25 which will engage apertures 27, when the needle cylinder loses one half revolution. Also at the completion of the continuous rotary knitting of the foot, cam 55 through cam lever 57 yieldingly moves auxiliary cam 64 into position to cause the long butt needles to ride down inclined surface 64^a to a position below the lowest point of switch cam 37; the long butt needles then are raised to their normal operative position by riding up inclined surface 40^c beneath said switch cam (Figs. 4 and 5). Following the latter positioning of auxiliary cam 64, switch cam 37 is moved inwardly by cam 51 through lever 49 to the position shown in Fig. 4 to effect the raising of the short butt needles to inoperative position. After the needles are thus positioned, cams 51 and 55 respectively disengage from cam levers 49 and 57, thereby permitting springs 47 and 69 to draw back switch cam 37 and auxiliary cam 64 to their original positions out of the path of the needles.

It will be seen that as the needle cylinder has lost one half of a revolution at the completion of the continuous knitting of the foot of the stocking, and as the long butt needles are moved into and the short butt needles are moved out of operative positions, that the continued operation of the machine will effect the knitting of the toe pocket on the upper side of the foot diagonally opposite to the heel pocket.

After the completion of the toe pocket, cam 35, through the connecting mechanism, again causes the needle cylinder to lose one half revolution which brings the needle cylinder back to its original position in respect to the other operative parts of the machine, the needle cylinder losing a complete revolution during the knitting of a stocking.

While I have herein disclosed a single embodiment of my invention, it is to be understood that it is but one of many which might be employed and still be within the scope of the appended claims.

Having thus described my invention I claim as new and desire to secure by Letters Patent.

1. A hosiery knitting machine comprising in its construction, a needle cylinder, needles

- mounted thereabout, means for operating said needles to knit a stocking with automatic means for causing said needles to lose a partial course of stitches prior to the knitting of the toe pocket to effect the knitting of the latter on the upper side of the foot.
2. A hosiery knitting machine comprising in its construction a needle cylinder, needles mounted thereabout, means for rotating said cylinder to effect the knitting of a stocking, with automatic means for causing said cylinder to lose approximately one-half revolution preparatory to the knitting of the toe pocket of the said stocking on the upper side of the foot.
3. A hosiery knitting machine comprising in its construction a needle cylinder, needles mounted thereabout, means for rotating said cylinder to effect the knitting of a stocking, automatic means for causing said cylinder to lose approximately one-half revolution preparatory to the knitting of the toe pocket of said stocking on the upper side of the foot, with automatic means for causing said cylinder to lose a second half revolution at the completion of the toe pocket of the said stocking.
4. A knitting machine comprising in its construction a needle cylinder, a shaft, means for effecting the rotation of said needle cylinder by the rotation of said shaft, automatic means for disconnecting said needle cylinder from said shaft for a predetermined period to cause said cylinder to lose approximately one-half revolution and thereby change the position of said needle cylinder relative to its driving mechanism.
5. A knitting machine comprising in its construction a needle cylinder, a shaft, means for effecting the rotation of said needle cylinder by the rotation of said shaft, automatic means for disconnecting said needle cylinder from said shaft to cause said cylinder to lose approximately one-half revolution and thereby change the position of said needle cylinder relative to its driving mechanism, with means whereby said needle cylinder is brought back to its original position relative to its driving mechanism.
6. In a knitting machine the combination of a needle cylinder, needles mounted thereabout, means for rotating said needle cylinder, a main cam drum shaft, with means controlled by a cam on said main cam drum shaft for disconnecting said needle cylinder and said means for rotating said needle cylinder for a predetermined period to cause said cylinder to lose approximately one-half revolution.
7. In a knitting machine the combination of a needle cylinder, needles mounted thereabout, means for rotating said needle cylinder, a main cam drum shaft, means controlled by a cam on said main cam drum shaft for disconnecting said needle cylinder
- and said means for rotating said needle cylinder for a predetermined period to cause said cylinder to lose approximately one-half revolution, with means controlled by said cam for connecting said needle cylinder and said means for rotating said needle cylinder after said predetermined period.
8. In a hosiery knitting machine, the combination of a needle cylinder, needles mounted thereabout, a beveled gear mounted on said needle cylinder and in mesh with a second beveled gear, mechanism for rotating said second beveled gear, with means for disconnecting said mechanism and said second beveled gear for a predetermined period during the operation of the machine to cause the cylinder to lose approximately one-half revolution.
9. In a knitting machine of the character described the combination of a machine frame, a needle cylinder, needles mounted thereabout, a stud projecting from said machine frame, a beveled gear mounted on said needle cylinder, a second beveled gear journaled on said stud and in mesh with said first beveled gear, a spur gear mounted to rotate about said stud, means for rotating said spur gear, with means for alternately connecting and disconnecting said spur gear and said second beveled gear at predetermined intervals during the continued operation of the machine to cause rotation of said cylinder approximately one-half revolution and then cause the same to lose approximately one-half revolution.
10. In a knitting machine of the character described the combination of a machine frame, a needle cylinder, needles mounted thereabout, a stud projecting from said machine frame, a beveled gear mounted on said needle cylinder, a second beveled gear journaled on said stud and in mesh with said first beveled gear, a spur gear mounted to rotate about said stud, means for rotating said spur gear, with means including a clutch hub mounted on said stud for alternately connecting and disconnecting said spur gear and said second beveled gear for predetermined intervals during the continued operation of the machine to cause rotation of said cylinder approximately one-half revolution and then cause the same to lose approximately one-half revolution.
11. In a knitting machine of the character described the combination of a needle cylinder, a beveled gear mounted on said needle cylinder, a stud, a second beveled gear journaled on said stud and in mesh with said first beveled gear, a spur gear mounted to rotate about said stud, means for rotating said spur gear, a clutching device adjacent said spur gear, with means for operating said clutching device to alternately connect and disconnect said spur gear and said second beveled gear for predetermined inter-

- 5 vals during the continued operation of the machine to cause rotation of said cylinder approximately one-half revolution and then cause the same to lose approximately one-half revolution.
12. In a hosiery knitting machine the combination of a needle cylinder, a beveled gear mounted thereon, a second beveled gear in mesh with said first beveled gear, a spur gear, means for rotating said spur gear, a clutching device, with means for operating said clutching device for alternately connecting and disconnecting said spur gear and said second beveled gear for predetermined intervals during the operation of the machine to cause rotation of said cylinder approximately one-half revolution and then cause the same to lose approximately one-half revolution.
13. In a hosiery knitting machine the combination of a needle cylinder, a beveled gear mounted thereon, a second beveled gear in mesh with said first beveled gear, a main cam drum shaft, a spur gear adjacent said second beveled gear, a clutching device, with means including a cam on said main cam drum shaft for operating said clutching device for alternately connecting and disconnecting said spur gear and said second beveled gear for predetermined intervals during the continued operation of the machine to cause rotation of said cylinder approximately one-half revolution and then cause the same to lose approximately one-half revolution.
14. The combination with a needle cylinder having a series of short butt needles and a series of long butt needles mounted thereabout, and a yarn change drum shaft, of an element carried by said yarn change drum shaft for effecting the operative positioning of one series of needles, to knit the heel pocket of a stocking therewith, and for effecting the operative positioning of the other series of needles to knit the toe pocket of the said stocking.
15. In a knitting machine of the character described the combination of a needle cylinder, a series of short butt needles and a series of long butt needles mounted thereabout, a switch cam, means for positioning said switch cam to elevate said short butt needles into inoperative position, with means for lowering said long butt needles below the lowest point of said switch cam when in said position to elevate said short butt needles.
16. A hosiery knitting machine having a needle cylinder, a series of long butt needles and a series of short butt needles mounted thereabout, a switch cam, an auxiliary cam, means for positioning said auxiliary cam to lower said long butt needles below said switch cam, with means for positioning said switch cam to effect the elevating of said short butt needles.
17. A hosiery knitting machine having a needle cylinder, a series of long butt needles and a series of short butt needles mounted thereabout, a yarn change drum shaft, a switch cam, an auxiliary cam, means including an element carried by said yarn change drum shaft for positioning said auxiliary cam to lower said long butt needles below said switch cam, with means for positioning said switch cam to effect the elevating of said short butt needles.
18. A hosiery knitting machine having a needle cylinder, a series of long butt needles, and a series of short butt needles mounted thereabout, a switch cam, an auxiliary cam, means for yieldingly positioning said auxiliary cam to lower said long butt needles below said switch cam, with means for positioning said switch cam to effect the elevating of said short butt needles.
19. A hosiery knitting machine having a needle cylinder, a series of long butt needles and a series of short butt needles mounted thereabout, a switch cam, an auxiliary cam, means for radially moving said switch cam to effect the elevating of the short butt needles, means for moving said auxiliary cam in a direction parallel to the direction of movement of said switch cam to position said auxiliary cam to lower the long butt needles below said switch cam.

ALBERT E. STEWART.
